P. LIEBERKNECHT

KNITTING MACHINE

Filed Jan. 21, 1927

Inventor.

Paul Lieberknecht.

UNITED STATES PATENT OFFICE.

PAUL LIEBERKNECHT, OF CHEMNITZ, GERMANY, ASSIGNOR TO ERNST BOESSNECK GESELLSCHAFT MIT BESCHRÄNKTER HAFTUNG, OF EINSIEDEL, NEAR CHEMNITZ, GERMANY.

KNITTING MACHINE.

Application filed January 21, 1927, Serial No. 182,546, and in Germany May 12, 1926.

Knitting machines, particularly of the straight-bar type, are provided with a transfer comb whereby the pressed-off portions of a stocking leg are transferred to the needle bar for the knitting of the foot. In known machines the comb is carried by means of arms on a rock shaft which, in order to leave the essential working parts of the machine unobscured, is arranged below the level of the sinkers. With the rock shaft in this position, the transfer comb follows a circular path which traverses the needle path at a considerable angle, and the transfer is therefore unreliable and gives rise to throw-outs and to waste of time.

The object of the present invention is to provide means for rectifying the position of the rock shaft without obstructing the view, and the invention consists in arranging the shaft so that it can be raised to the level of the sinkers for operation and lowered when not in use.

Preferably the shaft is for this purpose mounted in brackets which are pivotally adjustable for varying the position of the rock shaft.

The invention is illustrated in the accompanying drawing by a sectional view of the arrangement.

The transfer comb *c* is held in forks *b* at the up-turned ends of arms *a* which are secured to the rock shaft *d*. According to the invention, the latter is mounted in brackets *i* secured to a shaft *k*, the latter being arranged over the table *e* in about the same position as the rock shaft in the old arrangement. Normally the arms and brackets are turned over into the position shown by dotted lines in the figure and will therefore be out of the way. When the comb is to be used, the elements are turned into the position shown by full lines, this position being determined by the abutment against the table *e* of nose pieces *m* on the brackets. In this position, the rock shaft will be on a level *f* substantially coinciding with that of the

sinkers *n*, and the circular path *g* of the transfer points of the comb will be substantially parallel and coincident with the needles *h* so that the transfer will be effected in a reliable manner.

I claim:

1. In a knitting machine having a needle bar and a transfer comb arranged respectively below and above the sinkers, arms carrying said transfer comb, a rock shaft holding said arms, and means for supporting said rock shaft so that it can be raised substantially to the level of the sinkers for operation and lowered when not in use, substantially as and for the purpose set forth.

2. In a knitting machine having a needle bar and a transfer comb arranged respectively below and above the sinkers, arms carrying said transfer comb, a rock shaft holding said arms, and means for supporting said rock shaft so that it can be swung parallelly with itself into and out of operative position, the shaft being substantially on a level with the sinkers in the operative position, substantially as and for the purpose set forth.

3. In a knitting machine having a needle bar and a transfer comb arranged respectively below and above the sinkers, arms carrying said transfer comb, a rock shaft holding said arms, and pivotally adjustable brackets supporting said rock shaft so that it can be swung parallelly with itself into and out of operative position, the shaft being substantially on a level with the sinkers in the operative position, substantially as and for the purpose set forth.

4. The structure claimed in claim 3, nose-pieces connected to the brackets, and an abutment for said nose-pieces determining the operative position of the rock shaft.

5. The structure claimed in claim 3 and a shaft forming the pivotal support for the brackets.

PAUL LIEBERKNECHT.

CERTIFICATE OF CORRECTION.

Patent No. 1,643,249.

Granted September 20, 1927, to

PAUL LIEBERKNECHT.

It is hereby certified that the above numbered patent was erroneously issued to "Ernst Boessneck Gesellschaft mit Beschränkter Haftung" as assignee of the entire interest in said invention, whereas said Patent should have been issued to the inventor said "Lieberknecht and Ernst Boessneck Gesellschaft mit Beschränkter Haftung", as joint owners of said invention as shown by the records of assignment in this office; and that the said Letters Patent should be read with this correction therein that the same may conform to the record of the case in the Patent Office.

Signed and sealed this 1st day of November, A. D. 1927.

Seal.

**M. J. Moore,
Acting Commissioner of Patents.**
